COMBINED MANNED SPACECRAFT WITH STAGED RE-ENTRY BODY

Clarence B. Cohen, Redondo Beach, Warren G. Koerner, Manhattan Beach, and Irvin N. Spielberg, Pacific Palisades, Los Angeles, Calif., assignors to Thompson Ramo Wooldridge Inc., Redondo Beach, Calif., a corporation of Ohio

Filed Jan. 2, 1964, Ser. No. 77,998

Term of patent 14 years

(Cl. D71—1)

FIGURE 1 is a plan view of a combined manned spacecraft with staged re-entry body showing our new design; FIGURE 2 is a side elevation view thereof; FIGURE 3 is a rear elevation view thereof; FIGURE 4 is a front elevation view thereof; and FIGURE 5 is a perspective view thereof.
We claim:

The ornamental design for a combined manned spacecraft with staged re-entry body, substantially as shown.
